(57) **CLAIM**

I claim the ornamental design for a porthole for a boat, as shown and described.

DESCRIPTION

FIG. 1 is a side view of a porthole for a boat of my new design; and,

FIG. 2 is a perspective view thereof on a larger scale.
No claim is made to features shown in broken lines in the drawings.

1 Claim, 2 Drawing Sheets

FIG. 1

FIG. 2
